METHOD OF MAKING A COMPOSITE ARTICLE

Glenn B. Moule, Akron, Ohio, assignor to The B. F. Goodrich Company, New York, N. Y., a corporation of New York

Application June 29, 1934, Serial No. 733,033

5 Claims. (Cl. 154—2)

This invention relates to methods of making composite articles of sheet material, and is especially useful in production of composite floor mats for automobiles.

5 It is the practice of the automobile industry at the present time to use floor mats having an impervious waterproof rubber face and a cushioning back of soft felted material.

The present trend of automobile design necessitates the use of non-planiform floors in which the under side of the floor is recessed to clear the transmission and the upper surface of the floor is correspondingly bulged. The problem of providing mats to conform to such floors, and at the same time to provide mats having a pleasing appearance at low cost, is one which presents many difficulties.

10 The principal objects of this invention are to provide a method of making such mats which will reduce the cost and improve the appearance of the mats, and will eliminate the use of expensive apparatus.

15 Other objects will appear from the following description and the accompanying drawing.

20 Of the drawing:

Fig. 1 is a plan view of the rubber surface layer of a preferred form of mat before it has been formed to the contour of the floor.

Fig. 2 is a perspective view of a form with the 25 assembled mat thereon, part of the rubber surface layer being broken away to show the construction.

Fig. 3 is a perspective view of the finished mat in its preferred form.

30 Fig. 4 is a fragmentary cross section of the finished mat taken on line 4—4 of Fig. 3.

Referring to the drawing and particularly to Fig. 3, wherein one type of mat is shown to illustrate the method, the mat comprises an impervious waterproof rubber face 10, having cemented or otherwise secured thereto a backing 11 of loosely felted animal hair or other fibers. In order to conform to the floor of the car the mat is bent along lines 12—12' and 13—13' except through a central longitudinal portion 14 thereof which is elevated above the flanking portions of the mat and is bounded by sloping sides 15, 15'. This central raised portion merges into the inclined portion 16. The purpose of the elevated portion 15 is to clear the corresponding bulge in the floor which houses the torsion tube of the transmission of the car.

35 An ornamental border 17 is formed on the rubber surface of the mat. Various openings are provided through the mat to permit the control

mechanism to be passed therethrough, an opening 18 being provided for the gear shift lever, an opening 19 for the foot rest, and an opening 20 and 21 for the clutch and brake pedals.

5 In the manufacture of such a mat, I provide a form 22 comprising a sheet metal top 23 corresponding in contour to the desired mat and supported by suitable frame work. Marginal stops or guides 24, 24', and 25, 25' are fastened to the top 23.

10 Before starting to form and assemble the parts of the mat, the top 23 of the form is given a light coating of rubber cement along all its concave bending lines such as along lines 12, 12', and 13, 13' and around the base of the central bulged portion where it intersects the inclined portion.

15 A sheet of felt material 11 is cut, by means of dies or otherwise, to such a shape as to conform to the form. It is then sprayed on its upper face with a coating of a dispersion of rubber, either 20 natural or artificial, and permitted to dry somewhat. The felt layer is then laid over the form. Its lateral margins are placed against the stop strips 24, 24' and it is pressed about the form by hand manipulation. The extensibility of the felt 25 permits its being conformed smoothly to the central bulged portion of the form without cutting it. A light hand roller is used to smooth it in place, especially along the lines 12, 12', and 13, 13' and around the base of the central bulged 30 portion, where the light coating of cement on the form holds it in place.

35 The rubber face layer 10, which is of vulcanized sheet rubber, may be formed in continuous lengths with a ribbed or other ornamental design. The 35 border 17 may be printed, sprayed, or otherwise applied to the sheet material before it is vulcanized.

40 After vulcanization, the rubber material is cut to the form illustrated in Fig. 1 by means of suitable dies. In order to conform the rubber layer to the form without wrinkling of the material while providing sufficient material to cover the centrally bulged portion without stretching of the rubber, a crescent shaped aperture 26 is cut 45 from the sheet and a strip of material is removed to provide a central gap 27 extending from the nearest margin of the sheet to the center of the crescent shaped opening, the entire area removed being of forked shape.

50 Before applying the rubber facing to the felt, the underside of the facing is coated with an adhesive cement such as rubber cement or preferably the cement described in U. S. Letters Patent No. 1,892,123 and is then allowed to dry. 55

Strips 28 and 29, of adhesive rubberized tape, are applied over the felt material at such places as the edges of the rubber facing are to be joined.

The rubber facing is now applied over the felt and the tape. This is accomplished by first abutting one of the lateral margins of the rubber facing against one of the guides 24, 24' and then laying the sheet over the bulged portion of the form and adjusting the opposite margin against its guide strip. The margins adjacent the removed areas of the facing are then brought into abutting relation over the tapes 28 and 29 and the rubber layer is then rolled into contact with the felt by means of a hand roller.

As the rubber layer has been previously vulcanized, no further vulcanization of the mat is necessary.

As the forming of the rubber layer changes the included angle of the lateral margins with respect to each other, in cutting the material for the rubber facing the margins of the gap 27 are cut out of parallel by the amount of such change in angularity and the adjacent margins 30, 30' of the sheet are cut at right angles thereto, or out of alignment with each other by the amount of change of angularity and are aligned in the forming of the sheet to final shape. Similarly the marginal border along that side of the sheet is made to parallel the edges 30, 30'.

By molding the rubber layer as a flat sheet, the use of expensive molds is eliminated and the material may be produced on regular matting molds. As the mold surfaces are flat any ribbing or engraving may be clearly and accurately produced on the mold surfaces and is reproduced in the finished sheet.

After the mat is complete it is stripped from the form. Only sufficient adhesive is applied to the form to hold the material in place temporarily.

The apertures such as 18, 19, and 20 may be punched from the assembled mat after it is taken from the form.

I claim:

1. The method of making a non-planiform cushioned floor mat which comprises forming a layer of cushioning material about a former having the desired shape, applying inextensible adhesive tapes over restricted areas of the cushioning material, assembling a facing layer of vulcanized rubber over the cushioning material with its margins abutting each other over the taped areas and adhering the facing layer to the cushioning material.

5. The method of making a non-planiform cushioned floor mat which comprises forming a layer of extensible cushioning material about a form having the desired shape, applying inextensible adhesive tapes over restricted areas of the cushioning material, cutting a flat sheet of vulcanized rubber material so as to conform to the surface of the cushioning material without overlapping seams, and adhering the sheet to the cushioning material with its cut margins abutting each other over the taped areas.

10. The method of making a non-planiform cushioned floor mat which comprises forming a layer of extensible cushioning material about a form having the desired shape, applying inextensible adhesive tapes over restricted areas of the cushioning material, cutting a flat sheet of vulcanized rubber material to provide a surface layer having a forked area removed therefrom extending inwardly from a margin of the sheet, 15 and adhering said surface layer to the cushioning material with the margins of the sheet adjacent the removed area in abutting relation over the tapes.

20. The method of making a non-planiform cushioned floor mat which comprises forming a layer of extensible cushioning material about a form having the desired shape, applying inextensible adhesive tapes over restricted areas of the cushioning material, cutting a flat sheet of vulcanized rubber material to provide a surface layer having a forked area removed therefrom extending inwardly from a margin of the sheet, 25 and adhering said surface layer to the cushioning material with the margins of the sheet adjacent the removed area in abutting relation over the tapes.

25. The method of making a contoured article 30 of sheet rubber which comprises mounting a seaming strip of adhesive material upon a contoured form, so shaping a sheet of rubber that it can be fitted on the contoured form with two of its edge faces substantially abutting each other 35 at a position overlying the seaming strip, so mounting the rubber sheet upon the form, adhering it to the seaming strip, and then removing the assembly from the form.

40. The method of making a contoured mat 40 which comprises fitting a layer of fibrous material to a contoured form, so shaping a sheet of rubber that it can be fitted on the layer of fibrous material with two of its edge faces substantially abutting each other, so mounting the rubber sheet 45 upon the layer of fibrous material and adhering it thereto, and then removing the assembly from the form.

GLENN B. MOULE.
